CLAIM

The ornamental design for a spherical camera, as shown and described.

DESCRIPTION

FIG. 1 is a perspective view of a spherical camera showing my new design;

FIG. 2 is an exploded perspective view thereof, with a right cap and a left cap detached from a camera body;

FIG. 3 is a front elevational view thereof, the undisclosed rear elevational view being a mirror image of the front;

FIG. 4 is an exploded front elevational view thereof, with the right cap and the left cap detached from the camera body; FIG. 5 is a right side elevational view thereof, the undisclosed left side elevational view being a mirror image of the right side; and,

FIG. 6 is a cross sectional view of the spherical camera shown along the line 6-6 in FIG. 3.

The broken lines in the drawings are shown to illustrate the portions of a camera in which the design is embodied and form no part of the claimed design.
